UNITED STATES PATENT OFFICE.

HENRY LOUIS MORIN, OF SPRINGFIELD, MASSACHUSETTS.

SAFETY DEVICE FOR FEEDING CLOTHES TO WRINGERS.

Application filed February 6, 1926. Serial No. 86,600.

This invention relates to attachments for clothes wringers and particularly to an improved safety device for quickly and automatically turning off the power when a hand or other large object is moved a certain distance toward the rollers.

Another object of the invention is to provide an improved safety attachment which is an improvement over my prior Patent No. 1,537,864, wherein the power to the motor is automatically cut off instead of an actuation of a clutch for disconnecting the power.

A further object of the invention is to provide an improved safety device for wringers in which scrapers are provided to prevent the clothes passing through the wringer from adhering to the rollers thereof.

With the above recited and other objects in view, the invention resides in the novel construction set forth in the following specification, particularly pointed out in the appended claims and illustrated in the accompanying drawings, it being understood that the right is reserved to embodiments other than those actually illustrated herein, to the full extent indicated by the general meaning of the terms in which the claims are expressed.

In the accompanying drawings—

Figure 1 is a side view of a wringer with a safety device embodying the invention shown applied thereto.

Figure 2 is a view similar to Figure 1 but showing only part of a wringer and illustrating the safety device in an operated position.

Figure 3 is a top plan view of the structure shown in Figure 1.

Figure 4 is a sectional view through Figure 3 on line 4—4.

Figure 5 is a rear view of the safety attachment shown in Figures 1 and 2.

Figure 6 is a fragmentary view showing the electric switch and associated parts and illustrating how the switch may be locked closed.

Figure 7 is a detail fragmentary sectional view through Figure 3 on line 7—7.

Figure 8 is a detail fragmentary view similar to the structure shown at the left in Figure 4 but illustrating a modified arrangement of scraper.

In applying an embodiment of the invention to a wringer, it will be noted that the same may be applied to any of the wringers

now in common use where they are driven by electric motor. It will be understood that the detail structures of the wringer and motor form no part of the present invention.

Referring to the accompanying drawings by numerals, 1 indicates a support of any desired kind on which a wringer 2 is mounted. The wringer 2 is provided with brackets 3 which may be specially secured thereto by screws or otherwise and which fit into notches 4 in the extensions 5 on the side bars of frame 6. The frame 6 is provided with two side bars constructed as shown in Figures 1 and 2 and with suitable connecting and bracing bars 7 held in place by suitable nuts.

It will be noted from Figure 4 that nuts are provided on the bar 7 for spacing the side bars of frame 6. Rollers 8 and 9 are rotatably mounted on the frame 6, roller 8 having end plates or flanges 10 for holding the belt 11 in place and also for assisting in guiding the clothes as they are fed through the device. The belt 11 may be a combination of canvas and rubber or other desired material and is held taut by suitable springs 12 arranged in enlargements 13 on the respective side bars of frame 6. These springs act on journal blocks 13 (Figure 7) which press against the shaft 14 supporting the roller 8. A cross bar 15 is connected in any suitable manner with the extensions 5, said cross bar supporting a scraper 16 and a guiding plate 17. The scraper 16 may be made of a combination of rubber and canvas or other desired material and acts to in a certain sense, scrape or prevent clothes from following the belt 11 around roller 9. This scraper insures all of the clothes passing over belt 11 engaging the plate 17 and then the roller 18 of the wringer 2. The plate 17, together with the scraper 16, acts as a bridging structure for bridging the space between the rollers 9 and 18.

In order to prevent thin pieces of clothes or in fact, any piece of clothes from adhering to the rollers 18 and 18', there are provided scrapers 19 and 20 made of any desired material. These scrapers are clamped by bolts or otherwise to swinging arms 21 and 22. It will be noted that there are two arms 21 and two arms 22 and these respective arms are bolted or otherwise secured to the respective metallic holders 23 and 24 gripping the scrapers 19 and 20. The arms 21 are

preferably pivotally held in place by the respective pivotal pins 25' which hold the swinging frame 26 on an extension 27 of frame 6. A retractile spring 28 is connected to frame 6 for each of the arms 21 and at one end is connected to these arms for normally holding the scraper 19 against the roller 18'. Each of the arms 21 is also provided with a forwardly extending portion 29 (Figure 2) formed with a bent over section 30 adapted to be engaged by the thumb when it is desired to raise the scraper 19 off the roller 18'. The arms 22 are yieldingly held against the roller 18 by springs 31 connected to the respective arms and to the cross bar 15. Each of the arms 22 is provided with a forwardly extending section 32 which may be engaged by the hand of the operator and moved upwardly for swinging the scraper 20 away from roller 18. It will thus be seen that as the clothes are fed through the wringer, the scrapers 19 and 20 continually function to prevent any of the clothes from adhering to the rollers and, consequently, causing the rollers to continually function in a desirable manner.

In regard to the frame 26, it will be noted that the same is provided with a pair of side bars 33 and one of these side bars is formed with an extension 34 through which the rod 35 loosely extends, said rod having a nut 36 acting as an abutment and also an adjustable stop 37 for confining the spring 38 between the abutment and the enlargement 34. The frame 33 is supplied with a roller 39 which rests on the belt 11 when no clothes are being fed into the wringer. As the clothes are fed in, this roller is raised more or less according to the thickness of the clothes. The raising of the roller 39 swings frame 26 more or less and, consequently, compresses spring 38 to a certain extent. If a large object, as for instance, a hand, is forced beneath roller 39 as shown in Figure 2, spring 38 will be so compressed as to swing the lever 40 sufficiently to cause the extension 41 to engage the push button 42 for throwing the switch 43 to an open position. This will shut off the power to the wringer and, consequently, the hand will not be injured as the power is shut off before it can reach the rollers 18 and 18'. It will be noted that the wringer 2 is adapted to be driven by an electric motor of any desired kind and the motor is adapted to be connected to the wringer in any desired way but the circuit of the motor must pass through the switch 43. When the hand or large object has been removed from the position shown in Figure 2, the end 44 of abutment 42 is pressed and the switch again closed. If it should be desired to wring comparatively thick articles, as for instance, blankets, the frame 26 would naturally be elevated to such an extent as to occasionally throw off the power which would be objec-

tionable. To prevent this action, a vertically sliding plate 45 is provided, said plate being loosely carried by the upright 46 which also carries a switch 43 and which is secured in any desired manner to the extension 27 of frame 6. As the thick clothes are being forced into the machine and the operator observes that the switch 43 is about to be opened, plate 45 is raised so that the slight movement of the pin 42 caused by the first movement of lever 40 will cause the pin to press against plate 45 and hold the same in place as long as the thick article is being passed through the wringer. As soon as the thick article has passed through the wringer, frame 26 will immediately drop to a lower position which will relieve the pressure on the abutment 42 and the plate 45 will drop to the position shown in Figure 2 so that the safety device is again in functioning position.

It will be understood that the roller 9 may be driven from a wringer in any desired manner, as for instance, by a train of gears or a chain as shown in Figures 1, 3 and 4. When either a chain or train of gears is used, preferably a suitable housing is used for covering the parts. It will also be evident that the scrapers 19 and 20 may be connected to a stationary part of the wringer instead of to the frame 6 as illustrated in Figure 8. From this figure it will be noted that the scrapers function to remove the clothes from the rollers but are pivotally mounted on the wringer 2 and held in operative position by suitable springs. In driving the belt, the same may be driven by different means as heretofore described but under some circumstances it may be desirable to drive the belt through the use of special gears or cog wheels meshing with the special gears now in use on all wringers. In using gears of this kind or in using the chain drive as shown in the drawings, the device could be shifted from one side to the other so as to be used on either side of the wringer.

What I claim is:

1. The combination of a wringer driven by an electric motor with a safety device for feeding clothes thereto, comprising a feeding belt for feeding clothes to the wringer, a swinging frame positioned to normally rest on the belt by gravity, an electric switch interposed in the circuit of said motor, said switch being provided with a switch pin, a swinging arm adapted to engage said pin for shifting the same so as to open the switch, and means for connecting said arm with said swinging frame whereby when said frame is swung a predetermined distance from the belt said switch will be opened and the wringer stopped and a sliding member adapted to be manually moved to a position across the path of movement of

said switch pin for preventing the actuation of said pin, said sliding member being adapted to move under the action of gravity out of the path of travel of said pin when 5 the pressure of the pin on the parts has been removed.

2. In a safety device for feeding clothes to a wringer provided with an electric motor for driving the same, of a switch interposed 10 in the circuit of the motor of the wringer, said switch being provided with a sliding pin used for opening and closing the switch mechanism, means for feeding clothes to the wringer, said means including a swinging 15 frame, means operated by said swinging frame for engaging said pin and shifting the same in one direction and for opening said switch, and a sliding plate adapted to be manually moved to a position across the 20 path of movement of said pin for preventing the actuation of said pin, said plate being adapted to move out of the path of

travel of said pin when the pressure of the pin on the plate has been removed.

3. The combination of a wringer driven 25 by an electric motor with a safety device for feeding clothes thereto comprising a feeding belt, a swinging frame positioned to normally rest on the belt by gravity, a bracket carrying said swinging frame, an 30 electric switch interposed in the circuit of said motor, said switch being mounted on said bracket, a swinging arm carried by said bracket, resilient means connecting said arm and frame whereby the frame when it 35 is swung upwardly away from the belt will yieldingly act on said arm and said arm in turn will act to open said switch and manually actuated means for preventing the opening of said switch, said manually actuated 40 means moving out of the way of said switch under the action of gravity when pressure on the switch has been released.

HENRY LOUIS MORIN.
